DESIGN FOR A GAME CABINET

Ripley Wade, Mobile, Ala.

Application March 17, 1947, Serial No. 137,678

Term of patent 7 years

(Cl. D34—5)

To all whom it may concern:

Be it known that Ripley Wade, a citizen of the United States, residing in Mobile, in the county of Mobile and State of Alabama, has invented a new, original, and ornamental Design for a Game Cabinet, of which the following is a specification, reference being had to the accompanying drawing, forming a part thereof, wherein:

The dominant features of the design reside in the tapered shape shown more particularly in Figure 1.

I claim:

The ornamental design for a game cabinet, as shown and described.

RIPLEY WADE.
